UNITED STATES PATENT OFFICE.

ALRIK JOHNSON, OLOF PERSSON, AND PETE JOHNSON, OF KELLIHER, SASKATCHEWAN,
CANADA.

OIL CAN, LUBRICATOR, AND THE LIKE.

Application filed May 24, 1926, Serial No. 111,349, and in Canada May 11, 1926.

Our present invention appertains generally to improvements in the art of oil cans, lubricators and the like, commercially known as plunger cylinder oil pumps, and specifically to a double acting device of this character, as described in the present specification and illustrated in the accompanying drawings.

The invention consists essentially of the novel features pointed out broadly and specifically in the claims for novelty following a description containing an explanation in detail of an acceptable form of the invention.

More specifically, our invention is analogous to hand actuated plunger cylinder oil pumps of that type designed to pump oil from either end of the oil receptacle.

The principal object of our invention is to provide an efficient pump of this character, extremely simple in construction, easy to manufacture and inexpensive from a maintenance view point.

Briefly, it includes dual parallel stationary ball-valved cylinders, both communicating with a common discharge spout. A reciprocatable unit comprising a plunger cylinder and a piston, operate in conjunction with said stationary cylinders to pump oil through the same. This pump unit is operated by a thumb actuated fulcrumed lever mounted upon the receptacle cover in convenient proximity to the receptacle handle.

The novel characteristics and advantages of our invention will be apparent by perusing the following specification in conjunction with the drawings hereunto annexed in which:

Fig. 1 is a transverse medial vertical section of an oil pump constructed in accordance with an acceptable embodiment of our invention, and

Fig. 2 is a similar view showing certain of the components in a relative position.

The receptacle with which my invention is associated may be of any approved design such as illustrated in the annexed drawings and generally indicated by the numeral 3, the same being provided with a detachable cover 4 which is retained in position by a locking ring 5, said detachable cover and locking ring having no direct bearing upon the subject matter of the present invention.

A spout 6 is secured to the cover 4 and

is provided with a prolongation 7 which constitutes the stationary primary cylinder of the pump. The lower end 8 of this cylinder is reduced to form a seat for a ball 9 tensioned thereagainst by the coil spring 60 11, the latter abutting the fixed abutment 12.

A stationary secondary cylinder 13 is connected to the primary cylinder 7 by the bypass 14 and is arranged parallel therewith. 65 A valve seat 15 is formed on the secondary cylinder 13 providing a seat for the ball 16 which is tensioned thereagainst by the coil spring 17. This coil spring may be fastened as at 18 to the primary cylinder 7 in 70 any approved manner such as by spot welding.

The pumping unit includes a plunger cylinder 22 which fits closely about the primary cylinder 7. Its lower end is reduced to provide a valve seat 23 against which the ball 24 seats, movement of which is limited by the cage 25. This plunger cylinder is tensioned downwardly by a coil spring 26 the upper end of which abuts the lower end of 75 the primary cylinder 7, while its lower end abuts said cage 25 and constrains the latter in the position shown. An arm 27 is welded or otherwise secured to the plunger cylinder 22 and is provided with a piston 28 mounted upon its upper end, which is reciprocated longitudinally of the secondary cylinder 13 upon reciprocation of the plunger cylinder 22. 80

A push rod 29, arranged parallel with 90 the primary cylinder 7, is welded to the plunger cylinder 22 and extends through the sleeve 30 on the cover 4. A lever 31, fulcrumed on the bracket 32 is pivoted to said push rod by the member 33. This lever 31 95 is arranged in convenient proximity to the receptacle handle generally indicated at 34 so that the operator of the pump may conveniently actuate the same with the thumb of the hand.

The lowermost position of the pump unit is clearly shown in Fig. 1. In this position it will be noted that the lower extremity of the plunger cylinder 22 extends in close proximity to the bottom of the can and to the place where the oil flows when the can is held vertical or is inclined slightly forwardly, as is customary in use. In pumping oil with the receptacle so held, upon depression of the lever 31 to the position shown in Fig. 100 105 110

2, the plunger cylinder 22 is carried longitudinally of the primary cylinder 7. When the lever 31 is relieved of pressure, the coil spring 28 will plunge the plunger cylinder 5 22 into the oil, which forces the ball 24 from the valve seat 23, so that the chamber in the plunger cylinder 22 is filled with oil. Upon the succeeding upward stroke, the pressure of the oil forces the ball 24 against its seat 10 and the ball 9 from its seat so that the oil will be forced into the primary cylinder 7 and be discharged through the spout 6. The ball 16 constitutes a closure for the by-pass 14 preventing the oil from being forced into the secondary cylinder 13. When the receptacle is held inverted or in an inverted inclined position, the oil accumulating at the top of the can is drawn into the secondary cylinder 13 when the lever 31 is relieved of 15 pressure and the coil spring 26 forces the plunger cylinder 22 and the piston 28 downwardly. Upon the succeeding stroke, the piston 28 is advanced towards the ball 20 adapted to co-act with the valve seat 19 and 20 the oil contained within the secondary cylinder 13 forces said ball to close and is forced past the ball 16 into the primary cylinder 7, forcing the ball 9 to seat against its seat 8, and then through the primary cylinder 25 7 and out the discharge spout 6.

From the foregoing it is obvious that we have provided an oil pump which is efficient in operation in that it will pump oil from the receptacle irrespective of whether the 30 same is held vertical or inverted; in which the parts are comparatively few and may be manufactured without elaborate and extensive facilities, and in which the parts will function for extensive periods without appreciable wear or breakage.

While the preferred embodiment of the invention has been described it is to be understood that minor changes in the details of construction, combination and arrangement of co-operating elements may be resorted to within the scope of what is claimed without departing from the spirit of the invention.

What we claim as new is:

50 1. The combination with an oil receptacle provided with a discharge spout, of a stationary primary valved cylinder in said receptacle connected with said discharge spout; a reciprocable plunger cylinder on said primary cylinder for delivering oil therethrough; a stationary secondary valved cylinder connecting with said primary cylinder; means carried by said plunger cylinder extending into the secondary cylinder and connecting with a piston in said secondary cylinder for delivering oil therethrough; and hand actuated means for reciprocating said plunger cylinder and associated mechanism.

65 2. The combination with an oil receptacle

provided with a discharge spout, of a stationary primary cylinder in said receptacle extending in close proximity to the bottom thereof; a stationary secondary cylinder parallel and connecting with said primary cylinder extending in close proximity to the top of said receptacle; a plunger cylinder reciprocable on said primary cylinder adapted to force oil thereinto; a piston carried by said plunger cylinder working in 70 said secondary cylinder, adapted to draw oil thereinto and discharge oil therethrough into said primary cylinder and out said discharge spout; and means operable from the exterior of said receptacle for actuating 75 said plunger cylinder and piston.

3. The combination with a receptacle provided with a cover and a discharge spout, of a stationary primary cylinder in said receptacle constituting a prolongation of said 80 spout; a check valve in the lower end thereof; a stationary secondary cylinder mounted parallel with said primary cylinder; a check valve for the upper end thereof; a by-pass connecting said primary and secondary cylinders; a check valve in said by-pass; a plunger cylinder on said primary cylinder; a check valve on the lower end thereof; a coil spring in said plunger cylinder abutting said primary cylinder for 85 actuating said plunger cylinder downwardly; a piston connected to said plunger cylinder working in said secondary cylinder; a push rod connected to said plunger cylinder extending through said receptacle cover; 90 and a thumb actuated lever for reciprocating said push rod.

4. The combination with a receptacle provided with a cover and discharge spout, of a primary cylinder constituting a prolongation of said discharge spout; a valve seat in the lower end of said primary cylinder; a ball constituting a valve in connection with said valve seat; a coil spring positioned within said primary cylinder tensioned 105 against said ball to seat the same; a secondary cylinder parallel with said primary cylinder; a valve seat in the upper end thereof; a ball forming a check valve in connection with said seat; a by-pass connecting said secondary cylinder to said primary cylinder for preventing displacement of said secondary cylinder; a second valve seat on the side of said secondary cylinder; a ball in said by-pass forming a check valve 110 in connection with said second valve seat; a second coil spring mounted in said primary cylinder tensioned against said ball in 115 said by-pass to seat the same; a plunger cylinder mounted upon said primary cylinder; a valve seat in the lower end thereof; a ball forming a check valve in connection with said last mentioned seat; a cage for 120 preventing displacement of said last mentioned ball; a coil spring positioned in said 125 cage.

plunger cylinder abutting the end of said primary cylinder and said cage, retaining the latter in position; an arm mounted upon said plunger cylinder; a piston on the end of said arm working in said secondary cylinder; a push rod mounted on said plunger cylinder extending through said cover; and a lever fulcrumed on said cover and pivoted to said push rod for reciprocating the same and said plunger cylinder and piston to force oil through said cylinders and discharge spout.

In testimony whereof, we affix our signatures.
